UNITED STATES PATENT OFFICE.

DELIA M. SIMPSON, OF CHICAGO, ILLINOIS.

DRINKING-CUP ATTACHMENT.

940,204.

Specification of Letters Patent. Patented Nov. 16, 1909.

Application filed February 26, 1909. Serial No. 480,122.

To all whom it may concern:

Be it known that I, DELIA M. SIMPSON, a citizen of the United States, residing at Chicago, in the county of Cook and State of Illinois, have invented a new and useful Drinking-Cup Attachment, of which the following is a specification.

This invention relates to a sanitary attachment or guard for drinking cups.

10 The object of the invention is in a simple, practical and inexpensive manner, to eliminate the danger of contracting contagious diseases attending the promiscuous use of cups or dippers at water-coolers and drinking founts, thus to remove one of the most prolific causes of transmission of disease germs, such as those of tuberculosis, typhoid fever, and the like, with which the public has to contend, and further to prevent discomfort and often positive suffering to persons who, from fear of contagion, will abstain from water when traveling long distances on boats and railway cars.

25 With the above and other objects in view, as will appear as the nature of the invention is better understood, the same consists in the novel construction and combination of parts of a sanitary attachment or guard for drinking cups, as will be hereinafter fully described and claimed.

30 In the accompanying drawings forming a part of this specification, and in which like characters of reference indicate corresponding parts:—Figure 1 is a view in perspective of a drinking cup equipped with the guard of the present invention. Fig. 2 is a vertical longitudinal sectional view through the guard and a portion of the cup. Fig. 3 is a perspective detail view of the 40 guard.

The attachment consists of a guard 1 shaped to fit the rim of a cup or other drinking vessel, and a suction tube 2 of cylindrical form and provided at its outer end with a 45 bead 3, although this may be omitted if desired. These parts are preferably of some non-oxidizable metal, such as aluminum, or of hard rubber, and the finished article will be compact in form, light in weight and 50 easy to carry, as it will occupy but small space in a pocket or hand-bag.

The guard embodies two members or flanges 4 and 5, that are longitudinally bowed on arcs of different circles, the curvature of the outer flange 4 being such as to

adapt it to lie closely against the exterior of the cup, and that of the flange 5 to cause it to project a sufficient distance from the cup to accommodate the tube without contact with the latter. The flanges will be 60 yielding in character to permit of the attachment being applied to cups of different diameters, and thus largely extend its range of usefulness. The bend or point of junction 65 of the two flanges is curved in order to permit ready and thorough cleansing, thus to insure the removal of any bacteria that might be carried off from the cup rim.

The flange 5 is provided intermediate of its ends and adjacent to the bend with an 70 upstanding collar or guide 7, which, as shown in Fig. 2, is obliquely disposed with relation to the flange 4, thus to cause the upper end of the tube to be most conveniently positioned for reception by the mouth of 75 the user, and its lower end to be removed from the adjacent wall of the cup, thus to preclude the withdrawing of any disease germs that might adhere to the latter, and which would be liable to be taken up with 80 the liquid if the tube were disposed close to or contacted with the wall of the container.

The tube is slidable in the collar, but fits therein tightly enough to secure a frictional resistance to movement sufficient to retain it 85 at any desired adjustment. The lower end of the tube projects downward into the cup to a distance that will permit the bulk of its contents to be removed without tilting to an angle that would allow the liquid to reach 90 or wash against the rim, and thus possibly become contaminated.

The edges of the flanges are curved, the broadest part being at the center of each, and this arrangement will cause the inner 95 flange to operate to preclude any escape of the liquid when the cup is tilted in use, and the outer flange to prevent the under lip of the user from coming into contact with the cup.

The removable feature of the tube is one of importance, as it will permit a broken one to be replaced by a new one, and thus preserve the guard, and further will allow all the parts of the attachment to be kept in 105 a thoroughly sanitary condition.

The guard will generally be constructed from a sheet of suitable material, partially bent upon itself, and bowed longitudinally to fit a drinking cup.

I claim:—

1. A sanitary attachment for drinking cups comprising a guard formed of two co-acting joined members curved to conform to the shape of the cup with the outer member more extended than the inner member, and a suction tube adjustably connected therewith.
2. A sanitary attachment for drinking cups embodying two cup-engaging members, and a suction tube adjustably connected with one of the members and obliquely disposed relatively to the other.
3. A sanitary attachment for drinking cups comprising two cup-engaging members, one of which is provided with an upstanding collar, and a suction tube adjustably mounted

in the collar and being obliquely disposed relatively to the other member.

4. A sanitary attachment for drinking cups comprising two longitudinally bowed cup-engaging members, the edges of which are curved, with the widest part of each at its center, a collar carried by one of the members and disposed obliquely relatively to the other member, and a suction tube adjustably mounted in the collar.

In testimony that I claim the foregoing as my own, I have hereto affixed my signature in the presence of two witnesses.

DELIA M. SIMPSON.
